UNITED STATES PATENT OFFICE.

JOHN B. HADAWAY, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

DRYING APPARATUS.

1,426,379.

Specification of Letters Patent. Patented Aug. 22, 1922.

Application filed December 11, 1918. Serial No. 266,276.

To all whom it may concern:

Be it known that I, JOHN B. HADAWAY, a citizen of the United States, residing at Swampscott, in the county of Essex and 5 State of Massachusetts, have invented certain Improvements in Drying Apparatus, of which the following description, in connection with the accompanying drawings, is a specification, like reference characters on the 10 drawings indicating like parts in the several figures.

This invention relates to drying apparatus and is herein illustrated as embodied in an apparatus for transferring parts of boots 15 and shoes from one locality to another and drying them during the transfer.

In the manufacture of boots and shoes it is customary to apply to parts of the shoes water, cement, or other liquid or viscous 20 substances which require that the parts be subsequently dried more or less. For example, it is customary to fold the edges of certain parts of the uppers such as tips; but before the tips are run through the folding 25 machine, they must be properly cemented. Freshly applied cement, however, is not as tacky as that which has been allowed to dry for an interval; and consequently the usual procedure is to run the tips through a cementing machine, whereby the margins to 30 be folded are coated with cement, then to allow the cement to dry somewhat, and then to run them through the folding machine.

In the drying of the cement and the transfer of the cemented pieces to the folding machine, considerable effort and attention on the part of the operator who does the transferring and times the drying are involved, and the general object of the present invention 40 is to provide a suitable apparatus which may be used to carry pieces of stock slowly from the cementing machine to the folding machine or which may be used in any case in which it is required to transfer 45 in a similar manner pieces of stock from one locality to another. It should be understood that the cementing and folding operations are referred to merely to promote clearness and brevity and that the apparatus 50 may be used wherever convenient even though no drying effect may be sought.

According to one feature of the invention there are provided a conveyor the buckets of which pass two localities from one to 55 the other of which pieces of stock are to be

transferred, a source of power to which the conveyor may be connected, and automatic means responsive to a predetermined extent of travel of the conveyor for disconnecting it from the source of power. By properly 60 selecting this predetermined extent and by spacing the buckets accordingly, the parts may be caused to come to rest always with one of the buckets near one of the localities and another near the other locality. If then 65 two machines which are adapted to perform successive operations upon a piece of work, such for example as a cementing machine and a folding machine, are located respectively at the two localities referred to, the 70 cementing machine operator may fill the buckets one by one with cemented pieces of work as they come into position. As soon as the first bucket which has been filled reaches the folding machine operator, that 75 operator may take them out and fold them; and thereafter at the end of each movement of the conveyor an empty bucket will be presented to the cementing machine operator and a filled bucket to the folding machine 80 operator. By this procedure the cemented pieces may without further attention be transferred from one machine to the other and properly dried during the transfer.

Another feature of the invention comprises means for engaging the conveyor to lock it from movement after a predetermined amount of travel. In the illustrative machine one of the belts of the conveyor is provided with spaced openings, and there is 90 mounted on the frame of the machine a locking member which is held against the belt during the movement of the conveyor and enters an opening when said opening comes into register with the pin. 95

These and other features of the invention including certain details of construction and combinations of parts will be described as embodied in an illustrative machine and pointed out in the appended claims. 100

Referring now to the accompanying drawings,—

Fig. 1 is an elevation of an apparatus in which the present invention is embodied, and

Fig. 2 is a fragmentary view showing the switch-controlling and locking mechanism.

A bench 3 has a top provided with an opening to permit the runs of a conveyor to pass through it. The bench is adapted to 110

support at opposite sides two machines which are to operate successively upon pieces of work, for example a cementing machine at the locality indicated at 5 and 5 a folding machine at the locality indicated at 7. The conveyor comprises two belts, one of which is shown at 9, the other being directly behind and in register with it, as is usual, and a plurality of buckets or receptacles 10 in the form of baskets 11 loosely suspended from rods 13, said rods being held at their opposite ends in lugs or ears 15 carried by the belts. The baskets 11 have skeleton frames, their sides and bottoms being 15 made of wire gauze or other material which will permit the free circulation of air. The belts pass around upper and lower pulleys 17 which are provided in their peripheries with grooves 19 to receive the lugs 15 and 20 thereby prevent slipping of the belts. There are four of these pulleys, two at the top and two at the bottom, the upper two being fast to opposite ends of the rotatable shaft 20 and the lower two fast at opposite ends of 25 the shaft 22, but inasmuch as the two upper pulleys and the two lower pulleys are in register with each other in the view shown, only one of the upper and one of the lower pulleys appears.

30 In the position of parts shown, which is a position of rest, one of the baskets of the left-hand run of the conveyor is located below the top of the bench adjacent the locality 5. Into this basket the cementing machine operator may drop the cemented pieces of work until the basket is filled. Another of the baskets is located with its bottom substantially flush with the top of the bench near the locality 7. From this basket 35 the folding machine operator may take the cemented pieces which have traveled slowly from the locality 5 and have been properly dried in the interval. The conveyor is caused to be moved in stages which correspond in extent to the distance between the baskets and always comes to rest with two of the baskets in the positions which have just been described.

30 The rods 13, and consequently the baskets 55 11, are equally spaced around the belts; and located adjacent the rods and respectively at uniform distances therefrom in one of the belts is a series of perforations 21 with which a switch-controlling and locking member 23 co-operates successively to hold the conveyor from movement, the movement of the end of the locking member into a perforation serving also to open a switch and thereby withdraw the driving power 60 from the conveyor as will now be described.

65 The shaft of the lower pulleys 17 is rotatable in bearings below the top of the table and that of the upper pulleys in bearings considerably above the table, the bearings being formed in uprights 25 which are

steadied by braces 27, said braces serving also to guide the filled baskets and prevent them from tipping. Fast to one of the lower pulleys 17 is a gear 29 which meshes with a worm 31 on a longitudinal shaft 33. 70 This shaft has fast to it a gear 35 which meshes with a worm 37 formed on the end of the armature shaft of a motor 39. Leads 41, 42 are provided to conduct electric current to the motor and lead from any source 75 of current, the lead 42 being broken for the interposition of a switch the movable member 43 of which is mounted on the lower end of a hand lever 45. This lever is pivoted at 47 near its middle to a bracket on the bench and at its upper end to the member 23 which is herein shown as a rod loosely slideable in guides carried by the bench. At the end of the rod 23 remote from the pivot 49 is a roller 51 which, when the conveyor is moving, is arranged to run on the perforated belt. A spring 53 tends at all times to hold the switch open and the rod 23 in its right-hand position.

80 The operation of the apparatus, as thus far described, is as follows: Supposing that the basket which is nearest the locality 5, where the cementing machine is mounted, has been filled, the cementing machine operator presses the lever 45 thereby with- 85 drawing the end of the rod 23 from the perforation in the belt and closing the switch. At once the conveyor begins to move slowly in the direction indicated by the arrow with the roller 51 running on the 90 belt and thereby maintaining the switch closed until the next perforation comes into position to permit the roller and the end of the rod to be forced into it by the spring 53, whereupon the source of power is dis- 95 connected and the conveyor stopped exactly in a predetermined position with two of the baskets again respectively adjacent the localities 5 and 7. Further operation of the 100 apparatus is merely a repetition of the cycle 105 which has just been described. If the baskets are all empty at the start, it is, of course necessary for the cementing machine operator first to get all the baskets above 110 the bench filled before the folding machine 115 operator will receive any work. It may be that the folding machine operator may at times desire to operate the conveyor, and to permit such operation a rod 123 having an elbow to provide space for passage of 120 the belt is fast to the rod 23 and has an operating handle 223 adjacent to the locality 7. By pushing on the handle 223 the same 125 result may be obtained as has been described above as resulting from manipulation of the lever 45. It will be understood that the switch may be held closed by either operator for any desired interval and that, under these conditions, the conveyor will 130 continue to move.

Although the invention has been set forth as embodied in a particular apparatus for use in transferring work from a certain machine to another, it should be understood 5 that the invention is not limited in the scope of its application to the particular apparatus which has been shown and described or to any particular use.

Having thus described my invention, 10 what I claim as new and desire to secure by Letters Patent of the United States is:

1. The combination with a conveyor, of a source of power, means for connecting the conveyor with the source of power, and 15 means engaging the conveyor to maintain the connection for a predetermined interval.

2. The combination with a conveyor, of a source of power, means for connecting the conveyor with a source of power, a member 20 engaging the conveyor to maintain the connection, and means including the conveyor for moving the member to break the connection.

3. The combination with a conveyor, of 25 a source of power, means for connecting the conveyor with the source of power, a member engaging the conveyor to maintain the connection, and means on the conveyor arranged to control the movement of the member 30 and thereby the connection.

4. An apparatus of the class described, having, in combination, an endless belt having spaced perforations therein, receptacles severally attached to the belt adjacent to 35 the perforations the distance of the point of attachment of each receptacle from the corresponding perforation being substantially uniform, means for driving the conveyor, and means for engaging the perforations 40 and for disengaging the driving means.

5. The combination with a conveyor, comprising an endless belt having spaced perforations therein, of a member extending into one of the perforations, a source of 45 power, and means for withdrawing the member from the perforation and for connecting the belt with the source of power.

6. The combination with a bench adapted for the performance of two operations in 50 spaced localities, of a conveyor comprising receptacles mounted on an endless carrier the opposite runs of which are located respectively adjacent to the localities, means for driving the conveyor, and means for 55 stopping it, the conveyor being constructed and arranged to prevent the stopping means from being actuated to bring the conveyor to rest unless one of the receptacles is near one locality and another near the other 60 locality.

7. An apparatus of the class described, having, in combination, a conveyor comprising belts and receptacles mounted thereon, one of said belts having an opening therein, locking means located in the path of the opening, and means for causing the locking means to enter the opening when the locking means and the opening are in register.

8. In combination, a frame, spaced pulleys mounted on said frame, belts running around the pulleys, a plurality of spaced receptacles suspended from the belts, and means acting automatically to lock the belts when any receptacle reaches a predetermined position.

9. In combination, a frame, spaced pulleys mounted on said frame, belts running around the pulleys, a plurality of spaced receptacles suspended from the belts, means acting automatically to lock the belts when any receptacle reaches a predetermined position, and a device for releasing said locking means.

10. An apparatus of the class described, having in combination, a frame, belts mounted on the frame, spaced receptacles 85 mounted on the belts, one of said belts having openings therein spaced to correspond to the spaces between the receptacles and a spring-pressed locking pin mounted on the frame and located in the path of the openings.

11. The combination with a conveyor comprising belts and receptacles mounted thereon, of a locking member held from movement in the direction of travel of the conveyor, means on one of said belts aligned in the direction of travel of the conveyor for engaging the locking member, means whereby the locking member may be disengaged from the conveyor, and means acting at all 95 times when the locking member is disengaged to move it into engagement with the next succeeding locking-member-engaging means.

12. The combination with a bench adapted for the performance of two operations in spaced localities, of a conveyor having opposite runs located to pass near the localities and extending through the top of the bench, said conveyor comprising an endless 110 carrier and spaced receptacles carried thereby, means for driving the conveyor, and means for automatically stopping it, said last-named means being constructed and arranged to cause the conveyor to come to rest with one of the receptacles near one locality and another near the other locality.

In testimony whereof I have signed my name to this specification.

JOHN B. HADAWAY.
